UNITED STATES PATENT OFFICE.

ELLIS J. WOOLF, OF MINNEAPOLIS, MINNESOTA, ASSIGNOR TO THE WOOLF VALVE GEAR COMPANY, OF SAME PLACE.

ENGINE.

SPECIFICATION forming part of Letters Patent No. 521,278, dated June 12, 1894.

Application filed July 24, 1893. Serial No. 481,297. (No model.)

To all whom it may concern:

Be it known that I, ELLIS J. WOOLF, a citizen of the United States, residing at Minneapolis, in the county of Hennepin and State of Minnesota, have invented certain new and useful Improvements in Engines; and I do hereby declare the following to be a full, clear, and exact description of the invention, such as will enable others skilled in the art to which it app-
10 pertains to make and use the same.

My invention relates to engines and has for its object to improve certain features of the construction, with a view of obtaining increased efficiency of fluid distribution.

15 A number of the important features of the invention are directed to the valve mechanism; which improvements were especially designed for use in connection with compound engines.

20 Other features of the invention are directed to a simple construction, for converting compounds into simple engines.

25 My improved engines embody certain of the inventions described and claimed in my former patent, No. 475,427, of date May 24, 1892, entitled "single cylinder compound engine;" but involve additional new features of radical importance, as will hereinafter appear.

30 The several features of my invention will be hereinafter fully described, and will be defined in the claims.

35 The accompanying drawings illustrate my invention, wherein, like figures and letters referring to like parts throughout the several views—

40 Figure 1 is a complete vertical longitudinal section, through a pair of single cylinder compound engines set tandem with my improved double passage valves applied thereto, and shown in their central position, the said view illustrating my invention, in its several different features, in the preferred form. Fig. 2 is a plan view of the valve seat shown in Fig. 1

45 with the valve-chest cover and the distribution valves removed, showing the supplementary fluid supply passages and their valves. Fig. 3 is a vertical longitudinal section through another form of tandem compound engines, 50 with the same valves applied thereto, as in Fig. 1, but shown in one of their extreme po-

sitions; and Fig. 4 is a vertical section through a pair of single acting compound engines, having the same valves, as shown in Figs. 1 and 3, but shown in their other extreme positions. It may be here noted, therefore, that the said three views, Figs. 1, 3 and 4, show valves of identically the same construction respectively, in their central position and in the two opposite extremes of their travel; and at the same time, the said views serve to illustrate the applicability of my improved valve to three different kinds of double compound engines. Fig. 5 is a longitudinal vertical section of a valve and valve-seat similar to Fig. 1, but with a single passage instead of a pair of passages, as shown in Fig. 1.

55 Referring to Fig. 1, the numerals, 1, 2, and 3, represent respectively, the cylinder, the valve-chest and the common valve rod.

60 A represents the pair of independent valves working on the double seat B and operated together by the common rod, 3. The valve-seat, B, is provided with high pressure ports b, low pressure ports b' and final exhaust ports c'. The valves, A, are provided with a pair of internal fluid passages, a, and, a', and with final exhaust cups or cavity c. The valves A are provided with outside lap, as shown at, a², and with inside lap, as shown at, a³; and 65 certain portions of the valve-seats, B, are treated as outside valve-port laps, as shown at, b², and inside valve port laps, as shown at, b³. The valve-seat, B, is depressed or cut down on its face, as shown at, b⁴, to permit 70 the fluid from the valve-chest to reach and enter the passage, a, of the valve, when the same is uncovered by traveling over the depression, b⁴. The passage, a, in the valve has the function, in one position of serving as a 75 valve-port, to admit fluid to the cylinder port, b; and, for this reason, is termed a valve-port, and the heretofore referred to valve-port laps, b², and, b³, on the seat, are so-called with reference to the valve-port a.

80 The valve seats, B, in Fig. 1, are formed on a pair of cylinders 4 arranged tandem. In these cylinders, are placed a pair of pistons 5, connected by a common trunk 6, working through the central partition 7, which trunk 85 serves the usual function of reducing the area of the high pressure ends. The two pistons

5, are connected to the common piston rod proper 8. The trunk 6, is recessed, or otherwise provided with separate chambers, 9, at its opposite ends, with openings 10, for the inflow and outflow of the fluid; which chambers or recesses 9 serve to afford extra clearance for the high pressure ends of the cylinders. The part marked 6, and provided with the recesses marked 9, has been, in accordance with common usage, called a trunk; but it might, of course, be considered as an enlarged piston rod provided with the said recesses, 9, for the purposes named. The propriety of this language may be readily seen, 15 by noting that the so-called piston rod proper, marked 8, might be, and, in practice, is sometimes attached to only one of the pistons, instead of being extended through the trunk and connected to both pistons.

20 In Fig. 3, a different form of tandem compound is shown, having identically the same valves and substantially the same form of double valve seat, as in Fig. 1, so far as the action of these parts is concerned. In this form of engine, however, the high pressure cylinder 11, and the low pressure cylinder 12, and their respective pistons 13 and 14, are of different sizes, and no trunk is employed. The said cylinders and pistons are placed 25 30 tandem; and the pistons are connected by a common rod 15, working through the partition wall separating the two cylinders.

Let it be here noted, that the construction shown in Fig. 3, is, in fact, a double compound engine. The outer ends of the cylinders, 11 and 12, and the outside surfaces of the pistons 13 and 14 co-operate, under the control of the right hand valve; and the inner ends of the said cylinders and the said 35 40 pistons co-operate, under the control of the left hand valve.

Referring to Fig. 4, the valves and the valve-seats are identical with the construction of the same parts, as shown in Figs. 1 and 3; but are 45 shown as applied to a pair of single acting compound engines. In this view, Fig. 4, 16 represents the two high pressure cylinders; and 17 the two low pressure cylinders. 18 are the high pressure pistons and 19 the low pressure pistons. 20 represents the high pressure piston-rods and 21 the low pressure piston rods; all of which, in practice, could be dispensed with and substituted by trunks. The said four pistons would, of course, in practice, be all connected to a common powershaft, (not shown;) with the cranks, for the co-operating high and low pressure pistons, arranged one hundred and eighty degrees apart. From what has 55 already been said, and from the inspection of 60 the drawings, it is obvious that, in each of the said views, Figs. 1, 3 and 4, a double compound engine is shown, each member in each of which cases is coupled to a common valve-rod. As shown, the double valve-seat and 65 the pair of valves open to the common valve chest 2; but, it is, of course, obvious that a separate valve-chest might be provided

for each of the pair of valves, and these separate chests might receive their supply of fluid from independent sources. Let it now 70 be recalled, that in Fig. 1, the valves, A, are shown in their central position; that in Fig. 3, they are shown in their extreme left hand position; and that in Fig. 4, they are shown in their extreme right hand position. Also 75 assume that the supplementary valves D' are in their closed position. With these facts in mind, the actions of the valves on the compounds, may be readily traced, which actions are as follows: Let attention be directed to the left hand valve. When the said valve is at the extreme left end of its travel, as shown in Fig. 3, the high pressure cylinder port, b, is open to admission in the ordinary manner, at the right end of said 80 valve; and, the valve-port, a, is also open to admission, at b⁴, thereby providing a double sized admission area to the high pressure cylinder port b. In order to follow the fluid, assume, now, this same valve, of Fig. 3, to be in 85 the position as shown in Fig. 4, to-wit: at the extreme of its right hand travel. In that event, as will be seen by reference to Fig. 4, the valve-port or passage, a, will be in position to convey the fluid from the high to the 90 low pressure cylinder, and the valve passage, a', will also be in position to co-operate with the passage, a, for the same purpose, thereby rendering available a double sized admission 95 area to the low pressure cylinder port, b'. Now, to follow the fluid farther, let it again be assumed, that this same valve is in the position shown in Fig. 1, to-wit, central. In that event, the final exhaust from the low pressure cylinder would be about to begin through 100 the valve exhaust cup c into the final exhaust passage c', which leads, of course, to the atmosphere.

Referring to Fig. 5, the valve-seats, B, are identical with the valve-seats shown in Figs. 1, 3, and 4; and the valves, A', are similar to the valves, A, shown in the other views; but, differ therefrom, in the absence of the fluid passage, a', which fact also, of course, implies the absence of the inside valve lap, a³, shown 115 in the other views, as co-operating with that passage, a'. Otherwise stated, the valves A', shown in Fig. 5, have only the single fluid passage, a, which has heretofore been called the valve-port. The functions of this valve-port, a, in the said valves, A', are identical with the same passage in the before described valves A, giving the double admission area to the high pressure port, in one extreme position of the valve; and serving to convey, in 120 a reverse direction, the fluid from the high to the low pressure port, when the valve is in an opposite extreme position. But, in the absence of the passage, a', of course, the double 125 exhaust passage or admission area to the low pressure port, is not obtainable, with the said valves, A'.

In all the compound engines, hereinbefore referred to, by the use of the valves the valve-

seats, constructed as described, the admission of the fluid from the high to the low pressure port is delayed, until the piston has substantially completed its high pressure stroke.

5 With the valves, A, having the double or pair of fluid passages, a , and, a' , as shown in Figs. 1, 3 and 4, the co-operation of the inside valve lap, a^3 , and the so-called "inside valve-port lap, b^3 ," accomplishes this result; and in the 10 valves A', with the single fluid passage, a , the so-called "inside valve-port lap b^3 ," of itself, accomplishes this result. This particular result, of delaying the admission from the high to the low pressure port, was accomplished in 15 my former patent hereinbefore identified; but, in the said former patent, the lap, which accomplished that result, was treated as being on the inside wall of the valve cavity, and as covering or lapping the low pressure port.

20 The valve in said former patent was marked D, the fluid passage, d , the inner wall of said passage or cavity, as, d' , and the said lap as, d'' , the same being spoken of in said patent as "an outside lap d'' on the inside wall, d' of 25 the valve cavity d ." In this application, the special corresponding lap doing this work, has been treated as on the seat and lapping the valve-port, a ; and, for the purpose of better keeping up the numerous distinctions required, has been called, as above stated, the 30 inside valve-port lap, b^3 , to distinguish the same from the part of the valve-seat b^2 , which laps the said valve-port, a , on the other side, and is called the outside valve-port lap, b^2 .

35 The description so far given, is thought to have fully set out the construction and functions of the distribution valves A and A'. The construction of the trunk 6, in Fig. 3, with the chambers or recesses 9 and the advantage 40 of the same, for affording extra high pressure clearance, is also distinct.

45 Turning now to the other feature of my invention, to-wit: the construction for converting the compounds into simple engines, at will, I provide, for each high pressure cylinder, of each double compound engine shown, a supplementary fluid supply passage, D, for connecting the same with a source of fluid supply, and equip the said passage with a 50 valve, D' , controllable, at will, by a hand-rod D^2 , or other operating device. As shown, these supplementary supply passages, D, are obtained, by simply extending the high pressure cylinder ports outward, beyond the distributing valves, and providing them with an 55 opening into the valve-chest 2, as is best shown in Fig. 2; and, inasmuch, as in the construction shown, these passages, D, lie side-by-side, and near each other, the valves 60 D' covering the same, are connected to the common hand-rod D^2 . Of course, if, independent valve chests and sources of supply were provided for each distributing valve, as was hitherto stated might be done, the 65 said supplementary passages, D, would also communicate with the independent valve chests or independent sources of fluid sup-

ply. Regarding now the functions of the said supplementary passages, D, and their valves, D' , it is obvious that unexpanded fluid may be admitted to the high pressure cylinders independent of the distributing valves. Whenever this is done, the compounds are converted into simple engines, by rendering unexpanded fluid available on the low, as well as on the high pressure pistons. The value and importance of this feature are for starting the engines and especially for the increased power rendered available, by using the compounds as simple engines. 70 75 80

Referring to Fig. 4, for example, the supplementary valves, D' , are shown as in their open position. Hence, with the distribution valves, A, in the position shown in that view, unexpanded fluid will be admitted to both 85 high pressure cylinders, and also directly, from the source of fluid supply, to the low pressure cylinder of the left-hand engine. The result is, that the pressures on the high pressure pistons will neutralize each other, 90 and the whole pressure of the unexpanded fluid on the low pressure piston of the left hand engine, will become effective on the power shaft. Of course, in the opposite extreme positions of the distribution valve, with 95 the supplementary valves D' in the same position, open as shown, the right hand low pressure piston would become equally effective. If the distribution valves, A, be in their central position, and the supplementary 100 valves, D' , be in their open position, as shown in Fig. 1, unexpanded fluid will be admitted to both high pressure cylinders, but the pressures would neutralize each other, and as no fluid could pass to either of the low pressure 105 cylinders, the engine would be inoperative. But, if the distribution valves in Fig. 1, should be thrown into either of their extreme positions, as shown in Figs. 3 and 4, the low pressure pistons would become available as a simple 110 engine.

What is herein meant by the terms "independent valves" and "independent valve-seats," as applied to the distribution valves A A and A' A', is that the fluid distribution 115 effected thereby, for each compound, is independent of the other; or otherwise stated, none of the fluid used in the one compound ever commingles with that used in the other.

What I claim, and desire to secure by Letters Patent of the United States, is as follows:

1. In a compound engine, the combination with a valve-seat having a high and a low pressure port, of a valve having an internal fluid passage, which, in one position of the 125 valve, is uncovered and serves to convey the fluid to the high pressure port, and which, in the opposite position of the valve, serves to convey, in a reverse direction, the fluid from the high to the low pressure port, and means 130 for final exhaust operative to permit the exhaust from the low during the admission to the high pressure port, substantially as described.

2. In a compound engine, the combination with a valve-seat having a high and a low pressure port, of a valve having an internal fluid passage, which, in one position of the valve, is uncovered and co-operates with the ordinary opening to render available an increased admission area to the high pressure port, for a given valve travel, and which, in the opposite position of the valve, serves to convey the fluid from the high to the low pressure port, and means for final exhaust operative to permit the exhaust from the low during the admission to the high pressure port, substantially as described.
3. In a compound engine, the combination with a valve-seat having a high and a low pressure port, of a valve having two internal fluid passages, which, in one position of the valve, co-operate to render available an increased admission area to the low pressure port, for the given valve travel, and means for final exhaust operative to permit the exhaust from the low during the admission to the high pressure port, substantially as described.
4. In a compound engine, the combination with a valve - seat, having a high and a low pressure port, of a valve having, in addition to the final exhaust cavity, two internal fluid passages, one of which, in one position of the valve, is uncovered, and serves to convey fluid to the high pressure port, and both of which passages, in the opposite position of the valve, co-operate to render available an increased admission area to the low pressure port, for a given valve travel, substantially as described.
5. In a compound engine, the combination with a valve seat having a high and a low pressure port, of a valve having, in addition
- to the final exhaust cavity, two internal fluid passages, one of which, in one position of the valve, is uncovered and co-operates with the ordinary opening, to afford an increased available admission area to the high pressure port, for a given valve travel, and both of which passages, in the opposite position of the valve, co-operate with each other to render available an increased admission area to the low pressure port, for a given valve travel, substantially as described.
6. In a double compound engine, the combination with the two independent valve seats and the two independent valves on said seats, of a pair of independent supplementary fluid supply passages, each for connecting one high pressure cylinder with a source of fluid supply, and a valve in each of said passages controllable at will, for converting the compounds into simple engines, substantially as described.
7. The combination with two single cylinder compound engines set tandem and having their pistons connected by a common trunk, of the two valve-seats, the two valves on said seats reciprocating in common directions, a pair of supplementary fluid passages, for connecting the respective high pressure ends of the two cylinders with the respective high pressure valve chests, and valves in said passages controllable, at will, for converting the said compounds into simple engines, substantially as described.

In testimony whereof I affix my signature in presence of two witnesses.
